(57) **CLAIM**

The ornamental design for a portion of a shoulder pad as shown and described.

DESCRIPTION

FIG. 1 is a top plan view of a portion of a shoulder pad showing our new design;

FIG. 2 is a bottom plan view thereof;

FIG. 3 is a first end view thereof, shown in an upside down orientation;

FIG. 4 is a second end view thereof;

FIG. 5 is a first side elevation view thereof; and,

FIG. 6 is a second side elevation view thereof.

The long and short broken lines represent the bounds of the claimed design and form no part thereof; the evenly spaced broken lines show portions that form no part of the claimed design.

1 Claim, 2 Drawing Sheets
